UNITED STATES PATENT OFFICE.

ALEXANDER ROBERTSON, LUTHER S. RESSER, AND HARRY E. WHEELER, OF ALLIANCE, OHIO, ASSIGNEES TO AMERICAN STEEL FOUNDRIES, OF CHICAGO, ILLINOIS, A CORPORATION OF NEW JERSEY.

FLASK SHAKE OUT.

Application filed April 23, 1925. Serial No. 25,356.

To all whom it may concern:

Be it known that we, ALEXANDER ROBERTSON, LUTHER S. RESSER, and HARRY E. WHEELER, citizens of the United States, all residing at Alliance, in the county of Stark and State of Ohio, have jointly invented certain new and useful Improvements in Flask Shake Outs, of which the following is a specification.

10 The present invention relates to flask shakeouts.

More particularly the present invention relates to shaking means suitable for shaking the sand out of foundry flasks.

15 Shakers for this purpose have been provided in the past, but are open to objections for various reasons, among which it may be noted that certain prior shakers have involved handling of relatively heavy parts.

20 An object of the present invention is to provide a flask shakeout which may be stationarily mounted, which occupies a minimum of space in a shop, and which simplifies the matter of applying a flask thereto and removing said flask therefrom.

A further object is to provide a flask shakeout of simple construction which will be very efficient in service.

25 A further object is to provide a flask shakeout which cushions the shock relative to the foundation but permits a very efficient shaking of the flask or other device being treated.

A further object is to provide a flask shakeout which will stand up under all service.

30 Further objects will appear as the description proceeds.

Referring to the drawings—
40 Figure 1 is a sectional view illustrating one embodiment of the present invention, the section being taken along the plane indicated by the arrows 1—1 of Figure 2;

45 Figure 2 is a top plan view of the structure shown in Figure 1; and

Figure 3 is a sectional view taken along the plane indicated by the arrows 3—3 of Figure 2.

The numerals 1—1 indicate frame members, which may take the form of I-beams. Said frame members may be supported by any suitable foundation, as indicated by the numerals 2—2, which should permit ready access to the region beneath the frame mem-

bers 1—1. Connected between the frame members 1—1 are the two cross ties 3—3, which may be riveted to the frame members 1—1 to provide a sturdy structure. Mounted upon the cross ties 3—3 are a plurality of brackets 4—4 provided with upstanding pins 5—5. Said pins 5—5 are preferably located at the four corners of a rectangle and serve as supporting members for the springs 6—6.

The numerals 7—7 indicate bars, each 65 having head portions 8—8 at its two ends, which head portions are provided with recesses 9—9 for receiving the upper extremities of the pins 5—5. Said bars 7—7 rest upon the upper extremities of the springs 70 6—6, the lower extremities of said springs 6—6 seating upon outstanding portions of the brackets 4—4.

Each of the bars 7—7 has an enlarged portion 10 intermediate of its length, which 75 enlarged portions provide housings for vibrators 11. The details of the vibrators do not constitute the present invention and need not be disclosed in detail inasmuch as vibrators suitable for the purpose may 80 be purchased in the open market. It may be stated briefly, however, that each vibrator includes a plunger 12 housed within a cylinder 13, which cylinder 13 is held within the enlarged portion 10 by any preferred 85 means. Straps 14—14 are indicated for this purpose, which straps may be bolted or riveted to the bars 7—7. Each of the cylinders 13—13 is provided at its ends with a hardened steel plate 15 for receiving the blow of the corresponding plunger 12. Each of the vibrators 11 is provided with an air inlet 16, it being understood that the pressure of the air is controlled in any preferred way (not illustrated) for 95 causing the plunger 12 to have a rapid reciprocatory movement whereby to strike hammer blows against the plates 15—15.

The bars 7—7 present a horizontal surface upon which the flask 17 may be placed. 100

It will be clear that a violent shaking motion can be transmitted to said bars by the rapid hammer blows struck by the plunger 12 against the plates 15—15 in the vibrators 11. The violent shaking of the bars 7—7 105 is communicated directly to the flask 17, the effect of this shaking being the more marked by reason of the fact that the bars

7-7 are resiliently mounted upon the springs 6-6. A dancing motion is communicated to the flask, causing the sand to shake out more effectively than if the springs 6 are not provided. Not only is the advantage attained that the sand is shaken out more effectively, but the further advantage is attained that, due to the cushioned mounting of the bars 7-7, the frame members 10 1-1 are protected against the violent shaking communicated to the bars 7-7. The matter of maintaining foundations is therefore greatly simplified.

Inasmuch as the shakeout illustrated is 15 mounted upon a permanent foundation, and inasmuch as there is no necessity for lifting said shakeout, it is not necessary to provide a crane for lifting any part of said shakeout. Lifting means need be provided of only sufficient size to handle the flasks.

Though a preferred embodiment of the present invention has been described in detail, it will be clear that many modifications will occur to those skilled in the art. It is 25 intended to cover all modifications falling within the scope of the appended claims.

We claim:

1. A flask shakeout comprising relatively rigid supporting means, flask carrying means, resilient means between said supporting means and said flask carrying means, and reciprocating blow communicating means carried by said flask carrying means adapted to communicate a blow to 30 said flask carrying means at each end of its stroke.

2. A flask shakeout comprising supporting means, a flask supporting member, resilient means between said supporting means and said member, a cylinder carried by said member, and a reciprocable plunger within said cylinder adapted to communicate a blow to said member at each end of its stroke.

45 3. A flask shakeout including a pair of

spaced supporting members, a pair of cross ties between said supporting members, upstanding pins carried by said cross ties, springs upon said pins, and a pair of spaced bars having recesses adjacent to their ends 50 for receiving said pins, said bars being supported by said springs, said bars being provided intermediate of their length with vibratory means for communicating hammer blows to said bars.

4. A flask shakeout including a pair of spaced supporting members, a pair of cross ties between said supporting members, upstanding pins carried by said cross ties, 55 springs upon said pins, and a pair of spaced bars having recesses adjacent to their ends 60 for receiving said pins, said bars being supported by said springs, said bars being provided intermediate of their length with vibratory means for communicating hammer 65 blows to said bars, said spaced bars presenting a substantially horizontal upper surface for receiving a member to be shaken.

5. A flask shakeout comprising a relatively stationary supporting member, a flask 70 supporting member, resilient means for supporting said latter mentioned member on said first mentioned member, and blow communicating means housed within said flask supporting member and adapted to communicate a blow to said flask supporting member at each end of its stroke.

6. A flask shakeout including a pair of spaced supporting members, a pair of cross ties between said supporting members, a pair 80 of spaced bars, resilient means between said spaced bars and said cross ties, said bars being provided intermediate of their length 85 with vibratory means for communicating hammer blows to said bars.

Signed at Alliance, Ohio, this 17th day of April, 1925.

ALEXANDER ROBERTSON.
LUTHER S. RESSER.
HARRY E. WHEELER.
